CAP FOR RECEPTACLES

Joseph A. Hey, Decatur, Ill., assignor to Williams Sealing Corporation, Decatur, Ill., a corporation of Illinois

Application December 17, 1931, Serial No. 581,682

3 Claims. (Cl. 215—45)

This invention relates to caps for containers such as bottles, jugs, and receptacles which are provided with necks and/or nozzles. More particularly, it relates to the means for locking upon the necks or nozzles of such receptacles a cap having a skirt provided at its bottom with upwardly extending slots, with a divided clamping wire ring mounted in a discontinuous annular seat formed by rolling upwardly the bottoms of the 10 tongues formed between the slots, the ring having oppositely disposed hooks at its ends.

It has been the practice to employ with such rings a locking lever consisting of a wire so formed as to have at one end a pair of cam loops each 15 engaging a hook of the ring and adapted, by its downward movement, to draw the hooks toward each other, thereby to contract the ring and clamp the bottom of the skirt into locking engagement with the top of the neck or nozzle of 20 a container. As constructed heretofore, the operating handle of the lever has been formed by twisting together, below the loops, the ends of the wire of which the lever is formed, the lower 25 ends of the wire being in contact and parallel with each other and providing an operating end for engagement by the finger of the operator. It is the object of the present invention so to form the handle portion of the lever as to provide a more effective and smoother grip for the fingers 30 of the operator and to eliminate the sharp corners which have been provided heretofore at the ends of the parallel wires constituting the lower or operating end of the lever.

I accomplish the foregoing object and other and 35 more limited objects which will appear herein-after in and through the construction and arrangement of the parts shown in the drawing forming part hereof wherein Fig. 1 represents a perspective view of the top of a bottle having 40 a cap applied thereto to which there is applied a lever constructed in accordance with my invention; Fig. 2 is a front elevation of the lever and Fig. 3 a side elevation thereof.

Describing the various parts by reference characters, 1 denotes the neck of a bottle having applied thereto a cap 2 which is provided with a skirt 3 having slots 4 extending upwardly from the bottom thereof, the metal between the slots being rolled upwardly to form sleeves, as shown at 45 5 and 5a, thereby providing a discontinuous annular seat 4 for a clamping wire 6. The ends of the wire are formed into hooks 7 which are located in a wide slot 4a having a bearing sleeve 8 at the top thereof for engagement with the

cam loops of the lever thereby to retain the lever in locked position, as indicated in Fig. 1.

The parts thus far described are such as have been employed with the so-called "Kork-N-Seal" caps, as shown, for instance, in patent to Williams 1,214,734, issued February 6, 1917. The locking lever which is employed with the hooks 7 is indicated generally at 9 and consists of a wire having a central laterally extending portion 10 merging with cam loops 11, from which the wire branches 12 extend downwardly and are twisted together, as shown at 13, the lower portion of each wire branch being bent into approximately semi-circular form, as shown at 14, with their ends abutting and forming a circular eye 15. The lower operating portion of the lever thus formed extends transversely of the lever, the axis of the eye being substantially in the direction of movement of the lever. After the lower ends of the wire branches are brought into contact at 16, they are preferably united at this point, as by subjecting them to the action of a press, whereby they will be maintained in contact.

By lifting the lower end of the lever, the cams operate in the usual manner to permit the wire 6 to expand, thereby allowing the cap to be removed. By pressing downwardly on the lever to the position shown in Fig. 1, the cam loops operate upon the hooked ends of the wire 6 thereby to contract the bottom of the cap upon the neck of the bottle or other receptacle in a manner usual with the locking levers heretofore in use.

It will be noted that the central laterally extending portion 10 forms a cross bar or brace between the loops 11, which holds these loops in proper operative relation to the hooks 7. Furthermore, as will appear clearly from Fig. 3, this central cross bar or bridge 10 engages the upper ends of the branches 12 and prevents them from untwisting, even where a single twist is given to such branches, with the result that the ends 14 of the wire which form the eye 15 are prevented from getting out of line.

Among the advantages of the lever shown and described herein are the following: (a) the formation of a smooth circular eye at the lower end of the lever, thereby obtaining a greatly improved finger grip over that with which pre-existing levers have been provided; (b) the ability to make the lever of the same length as the former lever but with a single twist 13 of the branches 12 of the wire from which the lever is formed instead of with one and one-half twists which have been employed heretofore; (c) the security and stiffening of the single twist through closely abutting 105 110

the lower ends of the branches which form the eye as well as through the engagement of the central cross bar or bridge 10 with the upper portions of the branches 12.

5 Having thus described my invention, what I claim is:

1. In a closure cap of the character described having a skirt portion and a divided ring having hooked ends disposed adjacent each other, extending about said skirt portion, an operating lever formed from a single piece of wire, and having a pair of cam loops at one end operatively engaging the hooked ends of said ring, a cross bar connecting said cam loops, a body portion extending downwardly from said cam loops for operating the lever and formed by twisting the wire together, and an open eye in said body portion adjacent the lower end thereof.

2. A closure cap of the character described having a skirt portion, a divided ring extending about said skirt portion and having hooked ends disposed adjacent each other, a lever formed from a single piece of wire and having a pair of

cam loops engaging over the hooked ends of said ring, said lever having a laterally disposed central portion connecting said cam loops and a pair of branches extending downwardly from said loops, the ends of said branches abutting each other and forming an open eye having a smooth rounded lower end.

3. A closure cap of the character described having a skirt portion, a divided ring extending about said skirt portion and having hooked ends disposed adjacent each other, a lever formed from a single piece of wire and having a pair of cam loops engaging over the hooked ends of said ring, said lever having a laterally disposed central portion connecting said cam loops and a pair of branches extending downwardly from said loops, the ends of said branches abutting each other and formed into an open eye having a smooth rounded lower end, the axis of the eye being disposed substantially in the direction of movement of the lever.

JOSEPH A. HEY.
